UNITED STATES PATENT OFFICE.

ALEXANDER V. JENSEN, OF DEVILS SLIDE, UTAH, ASSIGNOR TO AMERICAN MANGANESE STEEL COMPANY, OF AUGUSTA, MAINE, A CORPORATION OF MAINE.

KOMINUTER OR LINING PLATE FOR BALL-MILLS.

1,174,160.

Specification of Letters Patent.

Patented Mar. 7, 1916.

Application filed February 15, 1915. Serial No. 8,125.

To all whom it may concern:

Be it known that I, ALEXANDER V. JENSEN, a subject of His Majesty the King of Denmark, and a resident of Devils Slide, in 5 the county of Morgan and State of Utah, have made and invented certain new and useful Improvements in Kominuter or Lining Plates for Ball-Mills, of which the following is a specification.

10 This invention relates to kominuter or lining plates for ball mills, and more particularly to the built-up type which includes a base and a detachable wearing portion or anvil.

15 An object of the present invention is to provide a base plate of such design and arrangement that it co-operates with the similar and adjoining plates, whereby all are held tightly and wedgedly against the surface 20 face of the shell of the ball mill.

25 A further object is to provide, in connection with the afore-mentioned bases, a novel wearing member or anvil which extends over and protects the holding bolts of the base to which it is secured, and in addition, is so arranged as to seat against the heel of the next adjacent base.

30 A further object is to provide a built-up kominuter plate including a base and a wearing portion or anvil, wherein a small area only of the base is exposed, and such exposed portion is enlarged so as to successfully withstand the comparatively small amount of wearing action it receives. The 35 enlargement of the heel end of the base also provides an abutment against which the wearing portion or anvil of the next adjacent kominuter rests.

40 The foregoing features prevent the buckling of the bases, provide for the ready and quick detachment and renewal of the anvils, and promote and insure the long and useful life of the kominuter plate.

45 Other objects and advantages will appear as the description proceeds, wherein it is to be understood that changes in the precise embodiment of my invention may be made within the scope of what is claimed without departing from the spirit of the invention.

50 The preferable form of my invention is disclosed in the accompanying drawings, wherein:—

Figure 1 is a view in side section of a shell of a boiler equipped with my improved

built-up or segmental kominuter plates; 55 Fig. 2 is a view in perspective of the base; and Fig. 3 is a view in perspective of a wearing portion or anvil, the same being preferably formed of manganese steel.

Referring to the several views wherein 60 corresponding parts are designated by similar reference numerals, each kominuter plate includes a base 5 which is formed as a curved plate and includes the toe 6 and the heel 7. A number of bolt openings 8 65 extend through the plate adjacent the toe and are relatively larger and of greater number than the second set of openings 9 which are located adjacent the heel of the plate and are provided with beveled side 70 walls.

The toe of the base is beveled as at 10, while as the heel of the plate is thickened or enlarged by the transversely extending rib 11, a portion of which projects beyond 75 the end of the heel and defines an overhanging ledge 12, the surface of which is beveled so as to receive the beveled toe of the next adjacent plate therebeneath. In this manner, the toe of one base projects beneath and wedgedly engages the heel of the next adjacent base, whereby all will be held tightly and wedgedly against the surface of the ball mill shell 13. A slight space 14 exists between the toe and heel of the meeting extremities of the bases, so that as the holding bolts 15 and 16 are tightened, the 80 bases will be firmly anchored in place and may shift to a slight extent for their proper and symmetrical arrangement.

90 A wearing block or anvil 17, preferably formed of manganese steel, due to the wearing qualities of such metal, is provided with the curved non-wearing face 18, which is adapted to rest snugly against the exposed 95 face of the base. The anvil includes the thickened head 19, which gradually tapers toward the remote extremity or heel 20. A number of openings 21 project through the anvil and aline or register with the main 100 openings 8 with which the base is provided. The main holding bolts 16 are provided with the beveled heads 22 which seat within the beveled openings 21, and in connection with the securing nuts 23, are adapted to 105 hold the anvil rigidly secured to, and in forced contact with, the base which is protected thereby. The enlarged head of the

anvil is provided with the recess 24 extending along the front and bottom edge thereof, which defines an overhanging ledge 25 into which the heel of the base of the adjacent kominuter plate is adapted to project, and against which the anvil seats. The supplemental holding bolts 15, which project through the heel of the base and through suitable openings provided therefor in the ball mill shell, are completely protected by the tapering heel 20 of the anvil, the latter projecting some little distance therebeyond and stopping adjacent the exposed rib 11 which forms the thickened heel of the base. In order to somewhat lighten the construction of the anvil and not in any wise interfere with the proper strength thereof, or reduce the amount of wearing metal therein, it is provided with suitable grooves, or recesses, indicated by the dotted lines 26.

The wearing blocks or anvils with which each base is provided are preferably formed of manganese steel, and may be easily and expeditiously removed and replaced from time to time, as it becomes necessary. The particular manner in which the bases are formed prevents their dislodgment, even though a number of the anvils be simultaneously removed, and, furthermore, the interlocking of the base and wedged engagement between the same hold them tightly and wedgedly against the shell of the ball mill and prevent their buckling. The thickened heel of each base, in addition to providing an abutment against which the anvil of the adjacent kominuter plate may rest, also reinforces the only exposed portion of the base and thus prevents the premature wearing of the same beyond service; the bases being thus adapted to outlast the life of several of the wearing blocks or anvils. The protection of the supplemental holding bolts 15 prevents their wear and disfigurement, and materially increases the serviceable life of the same.

Having thus fully described my invention, what I claim is:

1. A built-up kominuter plate comprising a base with a beveled toe and an undercut thickened heel, an anvil provided with a recess along its front extremity adapted to receive the thickened heel of the base of an adjacent kominuter plate, and means projecting through said anvil and base adapted to secure the same together, and to a supporting surface.

2. A built-up lining for ball mills comprising a base with main and supplemental

bolt openings, and a wearing block provided with openings adapted to align with the main openings in said base, and projecting beyond and protecting the supplemental openings within said base.

3. A lining for ball mills comprising a base with beveled ends adapted to interlock with the similar ends of the adjacent bases, and an anvil secured upon said base projecting above the heel of the adjacent base.

4. A built-up lining for ball mills comprising a base with main and supplemental bolt openings, and with a beveled toe and an undercut thickened heel adapted to receive the toe of an adjacent and similar base therebeneath, a wearing block provided with main bolt openings aligning with the main bolt openings of said base, said wearing block provided with an overhanging enlarged head projecting above the heel of an adjacent base, and with a tapering heel projecting across and protecting the supplemental bolt openings in the said base.

5. A built-up lining for ball mills comprising a base having a beveled toe and an enlarged heel defining an overhanging beveled ledge, a wearing block provided with an overhanging enlarged head projecting above the beveled toe of the base and defining therewith a recess adapted to receive the overhanging beveled ledge of the next adjacent base therein, and means for securing said base and wearing block in position within a ball mill.

6. A built-up lining for ball mills, comprising a base with main and supplemental bolt openings, a wearing block adapted to be engaged by means extending through the main bolt openings of the base, said wearing block projecting beyond and protecting the supplemental openings within said base.

7. A base for a built-up kominuter plate comprising a plate curved in its length, with a beveled front portion or toe, a transversely extending rib, materially thicker than said plate, formed integral with the rear portion or heel of said plate and projecting beyond and above the end thereof, and defining an overhanging beveled ledge adapted to receive the beveled toe of the next adjacent plate therebeneath.

Signed at Devils Slide, in the county of Morgan and State of Utah this 9th day of February A. D. 1915.

ALEXANDER V. JENSEN.
